UNITED STATES PATENT OFFICE.

JOHN W. HOWLAND, OF LINCOLN, NEBRASKA.

WIRE-FENCE TOOL.

SPECIFICATION forming part of Letters Patent No. 624,653, dated May 9, 1899.

Application filed December 20, 1898. Serial No. 699,808. (No model.)

To all whom it may concern:

Be it known that I, JOHN W. HOWLAND, a citizen of the United States, residing at Lincoln, in the county of Lancaster and State of Nebraska, have invented certain new and useful Improvements in Wire-Fence Tools; and I do declare the following to be a full, clear, and exact description of the invention, such as will enable others skilled in the art to which it appertains to make and use the same.

My invention relates to wire-fence tools; and the object is to provide a simple and effective device for building, tightening, and repairing wire fences.

With this object in view the invention consists in certain features of construction and combination of parts, which will be herein-after more fully set forth, and particularly pointed out in the claims.

In the accompanying drawing the figure is a perspective view illustrating my invention when used for tightening fence-wires.

11 denote the end posts, and 2 the wire to be stretched.

3 denotes a bracket having hinged arms 4, formed with sharp points 5, adapted to be driven into the posts to support the bracket in proper position. This bracket is provided with two apertured ears 6 6 and with hinged

7. The upper half of the apertured ears forms a hinge-section 6', by means of which the tightening-tool may be removably secured in place.

9 denotes the tightening-tool, which consists of a metallic rod or tube 10, split to form a tongue 11 and provided with ratchet-teeth 12, and the free end of the tool may be formed with a sharp point 13, which will be found useful in drawing staples. The opposite end

40 of the tool is provided with a rigid sleeve 14, in which the operating-handle is loosely mounted. The wire to be stretched has its end engaged with the split tongue, and by turning the tool in its bearings the slack of

the wire will be taken up. The wire now being stretched taut is held in this position by the pivoted pawl, thus allowing the operator to drive the staple into the post to hold the wire in its stretched position.

While I have shown the hooks 4 for securing the device to the fence-post, any other suitable means—as, for example, short chains provided with hooks at their free ends—may be employed; but I have not thought it necessary to illustrate this form, as their application is obvious.

The accompanying drawing shows my invention in the best form now known to me; but many changes in the details might be made within the skill of a good mechanic without departing from the spirit of my invention as set forth in the claims at the end of this specification.

Having thus fully described my invention, what I claim as new and useful, and desire to secure by Letters Patent of the United States, is—

1. The combination with the bracket, means for fastening it to a post or support, apertured ears formed on said bracket, and having a hinged section, a pawl pivoted to said bracket, and a winding-tool journaled in said ears and having a wire-grasping lip, and a ratchet-tooth, substantially as set forth.

2. The combination with the bracket, apertured ears formed in said bracket, and having their upper portion hinged on said bracket, pawls pivoted in said ears, and a winding-tool formed with radial teeth projecting into the path of said pawls, and an integral wire-grasping lip, substantially as set forth.

In testimony whereof I have hereunto set my hand in presence of two subscribing witnesses.

JOHN W. HOWLAND.

Witnesses:

F. A. BOEHMER,
MAY CALDWELL.
